UNITED STATES PATENT OFFICE.

FRED KESSEL, OF NEW YORK, N. Y.

CASTER.

1,352,004.

Specification of Letters Patent.

Patented Sept. 7, 1920.

Original application filed July 11, 1918, Serial No. 244,441. Divided and this application filed December 30, 1918. Serial No. 263,806.

To all whom it may concern:

Be it known that I, FRED KESSEL, a citizen of the United States, and a resident of the city of New York, in the county of New York and State of New York, have invented certain new and useful Improvements in Casters, of which the following is a specification, the same being a division of application for United States Letters Patent filed July 11, 1918, Serial No. 244,441.

The present invention relates to improvements in casters or, in other words, to a stand for supporting condiment-holders.

The main object of the invention is to provide a structure of this kind, on which a plurality of condiment-holders may be placed in such a manner that they can be conveniently removed therefrom, means being provided for covering the perforated caps of the said holders, to prevent foreign matter from entering the same.

Another object of the invention is to so construct the support that it is adjustable, according to the sizes of the condiment-holders.

A further object of the invention is to provide a stand of the type mentioned which is simple in construction, efficient in operation and which can be manufactured on a commercial scale, or, in other words, one which is not so difficult to produce as to be beyond the reasonable cost of such an article.

With these and other objects in view, which will more fully appear as the nature of the invention is better understood, the same consists in the combination, arrangement, and construction of parts hereinafter described, pointed out in the appended claim and illustrated in the accompanying drawings, it being understood that many changes may be made in the size and proportion of the several parts and details of construction within the scope of the appended claim without departing from the spirit or sacrificing any of the advantages of the invention.

One of the many possible embodiments of the invention is illustrated in the accompanying drawings, in which:

Figure 1 is a front elevation, partly in section, of a caster constructed in accordance with the present invention; Fig. 2 is a side elevation thereof; Fig. 3 is a perspec-

tive view of a portion of one of the condiment-holder supports; Fig. 4 is a similar view of another portion of said support; and Fig. 5 is a perspective view of a uniting element coöperating with the support portions shown in Figs. 3 and 4.

In the drawings, the numeral 10 indicates a heavy base, made of any suitable material and being of any suitable configuration. From this base rises a vertical standard 11, comprising two sections, denoted by the numerals 12 and 13. The section 12 is made in the form of a cylindrical bar, that is fixedly attached to the said base, and over this bar is drawn the section 13, in the form of a tube, the latter being rotatable around the said fixed section. To prevent disengagement of the two sections of the standard, there extends through the tube 13 a screw 14, the inner end of said screw being seated in a peripheral groove 15 in the section 12 of the said standard. This arrangement permits the tube 13 to be rotated upon the cylindrical bar 12.

Upon the tubular section 13 of the standard is shiftably disposed a member 16, a clamping screw 17 serving to hold the same in any desired position upon the said tubular section. To the said member 16 is attached a plurality of condiment-holder supports, in the present case two, denoted by the numeral 18. Each of these supports comprises a disk shaped base 19, attached to a resilient bracket 20, that is connected by a clamping screw 21 with a resilient bracket 22, the latter carrying a cover 23. The base 19 and the cover 23 are spaced apart in registering position, for a purpose herein-after to be described. The clamping screw extends through a longitudinal slot 24 in the bracket 22 and through a hole 25 in the bracket 20, and meshes with threads of a hole 26 in the member 16. In order to keep the brackets 20 and 22 in proper positions, there is drawn over the same a clip 27 of U-shaped cross-section, the body portion 28 of the said clip abutting against the front face of the bracket 20, and the flanges 29 of the said clip abutting against the sides of the two brackets of the support. The clip is provided with an aperture 30, through which the clamping screw 21 extends. The distance between the base 19 and the cover 23 of a condiment-holder sup-

port may be adjusted according to the height of the condiment holder. For making such adjustment, obviously, the clamping screw 21 is first loosened, after which the cover 23 of the support is shifted to the desired position, and the clamping screw 21 then set to clamping position. The slot 24 above mentioned permits of such adjustment.

The condiment-holders, denoted in the drawings by the numeral 31, are placed upon the bases 19 by either depressing such bases or by lifting the covers 23. When in place, the covers prevent foreign matter from entering the condiment-holders through the perforations 32 in the caps 33 thereof, and, also by reason of the resiliency of the brackets, keep the condiment-holders safely in place. The condiment-holders are removed from the supports by either depressing the bases 19 until the caps 33 thereof clear the covers 23, or by forcing the caps upward until the bottoms of the holders clear the bases 19.

What I claim is:—

A device of the character described, comprising a base, a standard rising therefrom made of two sections, one of said sections being fixed to said base and the other one being rotatable on said fixed section, a condiment holder support upon said rotatable standard section including two oppositely extending resilient brackets, one of which is provided with a longitudinal slot and the other one with a hole, a clip drawn over the meeting ends of said brackets provided with an aperture in alinement with said hole, a clamping screw passing through said hole, slot and aperture into said rotatable standard section, a base carried by one of said brackets, and a cover fixed in alinement with said second-mentioned base to the other one of said brackets.

Signed at New York, in the county of New York, and State of New York, this 2nd day of Dec., A. D. 1918.

FRED KESSEL.
